Specification for Design.

Patented May 27, 1913.

Application filed March 29, 1913. Serial No. 757,702. Term of patent 7 years.

To all whom it may concern:

Be it known that I, ERNEST W. HUTTIG, a subject of the Emperor of Germany, residing at Pittsburgh, in the county of Allegheny and State of Pennsylvania, United States of America, have invented a new, original, and ornamental Design for Lamp-Shades, of which the following is a specification, reference being had to the accompanying drawing, forming part thereof.

I claim:

The ornamental design for a lamp shade as shown.

ERNEST W. HUTTIG.
